UNITED STATES PATENT OFFICE

JOHN HAYS HAMMOND, JR., OF GLOUCESTER, MASSACHUSETTS

METHOD OF AND SYSTEM FOR ELIMINATING FADING

Application filed June 11, 1926. Serial No. 115,187.

This invention relates generally to radio transmission and receiving systems and more particularly to systems and methods for producing, transmitting and receiving signals substantially free from the effects of fading.

It is an object of this invention to minimize or overcome fading of radio telegraph and telephone signals. The hypothesis upon which this invention is based is that the angle of the antenna to the vertical and the consequent angle of radiation of energy therefrom, together with varying conditions of the upper atmosphere, determine the occurrence and location of localities of weak and strong signal reception during fading periods. Thus a vertical wire antenna may give at any given instant of time a fading pattern with the weak spots at certain locations, whereas if the antenna were tilted to a different angle the fading pattern at that instant would not have the weak spots in the same location.

As is well known, during a period of transmission at any given point sufficiently remote from a transmitter, the received signals may be strong for a period of time and then become gradually weakened until they almost or completely disappear. At a later time, the signals will increase and finally build up to as large a value as before the diminishing occurred. The period of fading and strengthening of signals may be of the order of a minute or two corresponding approximately to a frequency of fading of .01 cycle per second.

The present invention accomplishes the minimizing of fading by periodically and continuously altering the tilt of the antenna in any or all directions and thereby altering the tilt or angle of radiation of the radiated waves in such a manner that at any place radio energy will be available for signalling with fading intervals which are small compared with the time required for sending a signal. Thus for radio telegraphy, the frequency of fading is made high compared with the speed of sending dots and dashes and may be of the order of 1,000 cycles. For radio telephony the frequency of fading is

made high compared with the highest frequency of oscillations used and in speech or music may be of the order of 20,000 cycles per second. Thus for telegraphy the rate of fading is made roughly 100,000 times the original rate and for telephony roughly 2,000,000 times the original rate of .01 cycles per second. By this method every point of reception will be covered by a strong point of the radiant wave at a frequency which will not be detrimental to the usual reception of signals and on the other hand will cause certain portions of the messages to penetrate whereas otherwise they would not.

Accordingly, by swinging the antenna backward and forward at high speed any spot in the line of swing would be covered at least once during every cycle of tilt of the antenna and each spot, therefore, would receive energy at high frequency rate rather than at the slow rate dependent on the condition of the Heaviside layer as in present fading.

It is an object of this invention to perform the equivalent of tilting the antenna electrically.

The various features of the invention will be apparent from the following description of typical circuits illustrated in the accompanying drawings in which:

Fig. 1 is a diagram of an assumed fading pattern resulting from a vertical antenna at a given instant.

Fig. 2 is a similar diagram of a fading pattern resulting from a tilted antenna.

Fig. 3 represents an electrical equivalent of a vertical antenna and means for tilting it to and from a substantially horizontal position.

Fig. 3a is an illustrative diagram.

Fig. 3b is a diagrammatic representation of a receiver.

Fig. 4 is a diagrammatic representation of a transmitter having an electrical equivalent of a continuously tilted antenna adapted for telephony.

Figs. 5 and 6 are diagrams explanatory of the operation of a further embodiment of my invention.

Fig. 7 is a diagrammatic representation of

the last-mentioned embodiment of the invention, and

Fig. 8 is a further explanatory diagram.

With a transmitting antenna in a vertical position as at 1, Fig. 1, the field strength due to this antenna may vary with distance substantially as shown with maxima of intensity at locations 3, 5, 7, etc., and with minima of intensity at locations 2, 4, 6, etc. The positions of maxima and minima of intensity are created by and are dependent on reflections, interferences or refraction patterns due to phenomena in the upper atmosphere, and the unsteadiness which causes the alterations of the intensity patterns resulting in fading may be considered to be caused by an alteration in the upper atmosphere. Thus to produce energy at points 2, 4, 6, etc., with none at 3, 5, 7, etc., it is normally necessary to wait until the alteration in the upper atmosphere has occurred which will incur this result. However, the purpose of this invention is to cause energy to appear at 2, 4, 6, etc. as well as at 3, 5, 7, etc. by tilting the wave front, that is, changing the angle of radiation in a manner such as would be accomplished by tilting the antenna circuit as shown at 9, Fig. 2. Thus, if the tilting of the wave front from position 1 to or through position 9 is accomplished 1,000 times per second the energy will be caused to appear and disappear at any of the positions 2, 3, 4, 5, 6, 7, etc. at approximately 1,000 times per second, during what otherwise would be a fading interval.

The equivalent of a tilting antenna, as shown, includes a vertical antenna combined with a horizontal antenna pointing in the direction of a location at which a signal is to be received and fading eliminated.

The apparatus involved in carrying out my invention for telegraphy is schematically shown in Fig. 3. This comprises a vertical antenna VG and a horizontal antenna NS pointing toward a point of reception. Coils 10 and 11 are provided for the vertical antenna and coils 12 and 13 for the horizontal antenna by which they may be excited with alternating current power of the radio frequency to which the antenna systems are tuned. These coils may receive energy from coils 14, 15 of a rotor which may be turned to couple with either set of antenna coils or in part with both. This rotor is turned by a motor, for example, at 500 revolutions per second so that each antenna is actuated 1,000 times per second. The power source for actuating the antenna is alternator 18 or any other source of high frequency energy which feeds energy to the slip rings of the rotor by means of transformer 17. Key 16 is for the purpose of closing and opening the rotor circuit for the purpose of sending telegraphic signals. In operation with the key down and the rotor coupled to the vertical antenna the

initial field is the same as due to a vertical antenna 19-20, Fig. 3a. When the rotor has turned an eighth revolution the initial field will be the same as due to an antenna tilted at 45° as shown at 21-22, Fig. 3a. It is seen that the angle of tilt which can be from 0° to 90° passes through any intermediate value four times during each revolution. In consequence, a non-oscillating detector receiver of the usual type as exemplified by the circuit 24, Fig. 3b, will pick up energy subject to little or no fading.

For the purposes of radio telephony, it is seen that the rate of tilting of the initial field must be of higher frequency than speech frequency so that it becomes impractical to turn a rotor at the required speed. The strength of the currents in the antennæ, however, can be varied causing a tilt of the initial field which will produce substantially the same effect as a tilt of the antenna. A transmitter for radio telephony in accordance with this invention is shown in Fig. 4.

In accordance with this figure, the vertical antenna VG is actuated by coupling from coil 26 in the plate circuit of radio frequency amplifying vacuum tube 27, and the amount of current produced in the antenna is roughly proportional to the voltage across condenser 28. Similarly, the horizontal antenna NS is actuated by coupling coil 29 in the plate circuit of radio frequency amplifying tube 30 and the amplitude of the radio frequency oscillations is proportional to the voltage across condenser 31. Grid voltage for tubes 27 and 30 is supplied from coupling 32 to the oscillating circuit 33, 34 of a vacuum tube oscillator 35, which generates a current of a frequency to which the two antennæ are tuned. The grids of tubes 27 and 30 are excited in phase so that the waves of the two antennæ will be in phase. The resultant wave is therefore, plane polarized and not elliptically polarized as would be the case if a phase difference existed.

Tubes 36 and 37 with associated circuits are for the purpose of varying the tilt of the waves by changing the relative magnitudes of the radio frequency currents in the antennæ as determined by the frequency of oscillation of tube 38 and associated circuits. The couplings 39, 40 of the grid circuits of the tubes 36 and 37 to coil 41 of the oscillatory circuit of tube 38 are such that the charges applied to the grids of tubes 36 and 37 are of opposite phase, and as a result, when the plate current through coil 41 is highest, the plate current through coil 42 is lowest, so that the voltages across condensers 28 and 31 pulsate, with the voltage on 28 highest when the voltage on 31 is lowest, and vice versa. Consequently, the radio frequency power developed by the tubes 27 and 30 and impressed upon the vertical and

horizontal antennæ, respectively, fluctuates such that at one end of the cycle the radiation is a maximum from the vertical antenna and is a minimum from the horizontal antenna. At this instant the radiation is at a very small angle of tilt from the vertical. At the other end of the cycle, the horizontal antenna component of the radiated energy is at a maximum and the vertical antenna component at a minimum, and the angle of tilt from the vertical is large. In this manner, it is seen that the tilt of the wave is changed periodically, so that energy becomes available at a distant point at a high frequency rate.

The transmission of telephone messages is accomplished as usual by modulating the radiated energy. For this, modulator tube 43 is provided with current from the battery or generator source 44 delivered to the modulator tube 43 and the tubes 36, 37, 27, and 30, which are to be modulated through the common reactor 45, in the usual manner. When the grid circuit of tube 43 is suitably actuated at speech or other audio frequencies by means of microphone circuit 46 or other source of electrical audio frequency power, voltage variations are developed across reactor 45 in the usual way, causing plate modulation of the succeeding circuits. This modulation does not in any manner influence the ratio of horizontal radiation to vertical radiation from the antennæ nor the angle of tilt of the radiated wave, which are governed solely by the operation of circuits of tubes 27, 30, 36, 37, and 38.

The radio telephone signals may be received at a distant point by the usual non-oscillating detector circuit, such, for example, as is shown schematically in Fig. 3b, involving antenna 23, detector 24 and indicator 25.

It is to be understood that in reception with any simple antenna, a supersonic frequency component will be present in the received energy, corresponding with the frequency at which the rapidly changing wave front becomes that required for optimum reception with the said antenna.

Therefore, if desired, a system of double detection may be used, involving tuning to the radio energy, detecting to produce currents of intermediate frequency, or, frequency of tilt, amplifying, and again detecting to produce the original audio frequency currents.

The circuits shown in Figs. 3 and 4 may not eliminate fading in all directions. In order to eliminate fading in all directions, an arrangement may be used employing three antenna structures, all operating at the same radio frequency and preferably in phase. This modification of the method is indicated schematically in Figs. 5 and 6. With three antennæ NS, EW, and GV as in Fig. 5, all

actuated in phase or with 180 degrees opposition, there will be a resultant plane polarized radiation as if from a single antenna, GR. It is important that the antennæ be excited in phase or 180° out of phase in the high frequency sense, to avoid elliptically polarized radiations which result in directional transmission. The direction GR of the resultant field is controlled by relative magnitudes of component radiations and can be made to assume substantially all angles of tilt and orientation by varying the intensity of the component radiations by a double process. For example, one process or step involving the horizontal antennæ only, may make the combined effects of these two antennæ by themselves produce a rotating field, with the resultant horizontal radiation swinging from west to south, to east and to north, etc., without change of intensity. The frequency of rotation may be low compared with the radio frequency employed in radio transmission. This rotating horizontal field of unchanging resulting intensity when combined with the vertical field will produce a resultant due to all antennæ with a constant angle of tilt, say 45 degrees, but with the orientation changing in accordance with the horizontal rotating field, making the tilt to west, south, east and north, and all intermediate points in succession. In addition to this circular rotation of the field, a second process or step may change the relative energies of the horizontal and vertical fields so that all angles of tilt may be attained, making the resultant field cover all directions of orientation and all angles of tilt, in a time which is small in comparison with the period of the signal to be transmitted. This is shown in Fig. 6.

For telegraphy the frequency radiated may be of the order of 1,000,000 cycles, the frequency of rotation 20,000 cycles, and the frequency of tilting 500 cycles. For telephony, however, the angle of tilt must be changed at a much higher rate, say 20,000 cycles per second. This requires the rotation to be made, say at 100,000 cycles, for a carrier frequency of the order of 1,000,000 cycles. Modulation at the audio frequency rate changes the intensities of all radiations in unison, so that the rotation of the field in space is not affected, but only the magnitude of the resultant field is changed in accordance with the audio modulation.

A transmitter of this type is shown in Fig. 7 which is primarily a radio telephone transmitter, suitable for operating into an ordinary type receiver. It is arranged, however, with keys and switches in three places to permit telegraphy either by audio modulation, by intermediate frequency modulation, or by continuous wave telegraphy.

In this transmitter, the following frequencies are arbitrarily assumed for purposes of illustration and are as follows: The radio car-

rier frequency, 1,000,000 cycles per second, is determined by the frequency of the oscillations produced by tube 47 and associated circuits; the rate of rotation of the horizontal field, 100,000 cycles, is determined by the frequency of oscillation of oscillator tube 48 and associated circuits; the frequency of tilt, 20,000 cycles, is determined by the frequency of oscillation of tube 49 and associated circuits. For telephony the entire radiation is modulated in accordance with speech or other audio signals generated by microphone 50 and associated circuits. For audio telegraphy, the microphone may be replaced by throw of switch to cause the system to be modulated by electrical source 51, say 500 cycles, and for dot and dash by closure of key 52. Continuous wave signalling may be accomplished by keying the circuit of radio master oscillator 47 by key 53, which is held closed for other types of communication. For superaudible modulation, key 54 may be used, changing the rate of tilt from 20,000 to 19,000 cycles, for example. This latter key may be normally open for other communication, but this circuit may be keyed for multiplex work without interfering with radio telephony, or audio radio telegraphy. If a secrecy feature is desired, a wobbler mechanism may be applied to oscillator 47 to vary the radio carrier frequency to prevent continuous wave reception when key 53 is closed, without, however, interfering with the operation of the system as to quality of signals.

The three antennæ are driven from the output of three radio frequency power and amplifier circuits, the vertical antenna VG from tube 55, the east-west antenna from tubes 56 and 57, and north-south antenna from tubes 58 and 59. All of these tubes are excited in the grid circuit in unison from the output of master radio oscillator 47, and each grid is provided with the customary individual condenser and resistance for control of bias.

Tubes 56, 57, 58, and 59 and associated circuits are so arranged that the currents produced in antennæ EW, NS will be suitably related to produce a uniform horizontal field, with direction of the field rotating about the points of the compass at the assumed rate of 100,000 cycles as determined by the master oscillator tube 48. The tilt of the field resulting from the horizontal rotating field from antennæ NS and EW and the vertical antenna VG is altered in accordance with voltages developed across coils 60 and 61 by the action of tube 62, actuated by master oscillator tube 49. These voltages across 60 and 61 of frequency equal to the rate of tilt 20,000 cycles, are of opposite phase so that more power is thrown to the vertical field by coil 61, at the same time that less power is thrown to the horizontal field by coil 60 and

vice versa. The entire radio frequency field, tilted and rotated, may be modulated in intensity without change of directional relations by means of variations in voltage developed across choke coil 63, such variations in voltage being at audio frequency in accordance with telephone or telegraph signals impressed on the grid of the modulator tube 64.

It is seen from the above description that the tilting process is substantially the same as in Fig. 4, and that the same general method of modulation is used. The essential difference is that instead of exciting a single horizontal antenna by tube 30 of Fig. 4, two horizontal antennæ are excited in such a manner as to produce a rotating field, in the horizontal plane, through the operation of tubes 48, 56, 57, 58, 59 and the tube 65 and associated circuits.

The operation to produce this rotating field is as follows:

Tube 65 is actuated in the grid circuit from master tube 48, of 100,000 cycles frequency, and in the plate circuit by direct voltage except as modulated at the lower frequencies. For the present, we may consider the plate circuit supply to be steady, with tubes 62 and 64 not operative, that is without any grid excitation. As a result, the tube 65 produces output power of 100,000 cycle frequency. This power actuates primaries 66 and 67 of transformers which supply the amplifiers 56, 57, and 58, 59 with plate power. But the circuits are so adjusted by resistors 68, 69, and condenser 70 that the current to transformer 66 is 90 degrees different in phase from the current to transformer 67. Now the circuits of tubes 56 and 57 are of a type which give a modulated output in the antenna EW with carrier wave suppressed, accomplished in part by reversing the coils 71, 72, relatively to each other. Similarly, the tubes 58 and 59 give a modulated output in the antenna NS with carrier wave suppressed. But the phase of the modulation for the currents of the two antennæ differs by 90 degrees in time, and the antennæ themselves are located 90 degrees apart in space. Accordingly, it is readily seen that the resultant of the two fields due to the two antennæ will be an oscillatory high frequency field of constant magnitude, but rotating at a frequency of revolution equal to the frequency of currents of the supply circuits 66 and 67.

For, let the wave form for field due to the N-S antenna (Fig. 7) be given by

$$F_{ns} = A \sin pt \sin \omega t$$

in which A is a constant, p is an angular velocity corresponding to the rate of modulation (100,000 cycles) and ω an angular velocity corresponding to the carrier frequency, (1,000,000 cycles).

Then, because of the equal voltages, equal

tubes and equal antennæ for the two horizontal antennæ, the field due to the west-east antenna will be

$$F_{we} = A \sin (pt + \phi_p) [\sin (\omega t + \phi_w)]$$

in which ϕ_p and ϕ_w are constant phase angles. But due to the grids of all amplifier tubes being excited in parallel and therefore in phase, the phase angle becomes zero. Also because of the phase difference of modulation of 90 degrees, determined by the phase-splitting device, $\phi_p = 90^\circ$ and the west-east field becomes, on simplifying

$$F_{we} = A \cos pt \sin \omega t$$

By combining the effects of the two component fields, by a vector addition in space, we find the numerical resultant of the two fields is

$$F_r = \sin \omega t \sqrt{A^2 \sin^2 pt + A^2 \cos^2 pt} = A \sin \omega t$$

and is therefore an unmodulated field of amplitude A. Moreover, the direction of the field is given readily by the angle ϕ which the resultant field F_r makes with the east direction, that is,

$$\phi = \tan^{-1} \frac{A \sin pt}{A \cos pt} = \tan^{-1} \tan pt = pt.$$

That is, the angle ϕ is changing with angular velocity p , so that the resultant field traverses all points of the compass 100,000 times per second, and this constitutes the rotating field of constant magnitude, in the horizontal plane.

As in Fig. 4, so in Fig. 7, means are provided for varying the tilt of the waves by varying the power to the horizontal antenna and vertical antenna. On Fig. 7 this is done by tube 62 and associated circuits, which develops voltage across coil 60 for the horizontal antenna out of phase with the voltage across 61, inductively coupled to coil 60, for the vertical antennæ. The result is readily seen to produce a variation of the tilt of the wave from substantially vertical to substantially horizontal position. At a distant point in any direction energy will be made available, and when subjected to detection will produce currents corresponding to the audio modulation.

Thus reception can be used giving the speech or audio signals directly after the first detection, or if desired after first detection, amplifying and second detection. Further, if the key 54 is actuated, changing the frequency of tilting, these keyings may be used for telegraph purposes, without interfering with telephony or audio telegraphy. Or continuous wave telegraphy by itself may be accomplished by keying circuit 53, since this arrangement makes the carrier wave available at all points without fading, as well

as the side waves produced by the modulation processes.

Having fully and clearly described the principles involved in my invention I claim:

1. The method of eliminating fading in the reception of radiant energy which includes the step of continuously electrically varying the angle of tilt from vertical of the effective transmitting antenna from and toward a substantially vertical position, during radiation of the energy.

2. The method of eliminating fading in the reception of radiant energy which consists in transmitting energy from adjacent substantially vertical and substantially horizontal antennæ and varying cyclically the amounts of energy supplied to the respective antennæ.

3. The method of eliminating fading in the reception of radiant energy which consists in transmitting energy from adjacent substantially vertical and substantially horizontal antennæ and varying inversely the amounts of energy supplied to the respective antennæ.

4. The method of eliminating fading in the reception of radiant energy which consists in transmitting energy from adjacent substantially vertical and substantially horizontal antennæ and supplying energy to the antennæ in a manner such that at alternating times the energy is impressed almost exclusively on the vertical antenna and the horizontal antenna respectively and during the intervening periods impressing inversely varying amounts of energy upon the respective antennæ.

5. The method of eliminating fading in the reception of radiant energy which consists in cyclically varying the angle of radiation of the transmitted energy at a superaudible frequency lower than the carrier frequency.

6. The method of eliminating fading in the reception of radiant energy which includes the steps of cyclically varying the vertical angle of radiation of the transmitted energy and transmitting on a continuously rotating field.

7. The method of eliminating fading in the reception of radiant energy which consists in transmitting energy from a substantially vertical antenna and substantially horizontal antennæ arranged at right angles to each other causing said horizontal antennæ to produce a rotating field and electrically tilting the angle of radiation of the transmitted energy between limits determined by the vertical and horizontal antennæ.

8. Method of eliminating fading in the reception of radiant energy which consists in transmitting energy from adjacent substantially vertical and substantially horizontal antenna systems, causing said horizontal antenna system to produce a rotating field and

supplying energy to the two antenna systems in a manner such that at alternating times the energy is impressed substantially exclusively on one system and the other system respectively and during the intervening periods impressing inversely varying amounts of energy upon the respective antenna systems.

9. A transmitter for radiant energy enabling energy to be received without fading, comprising means for generating continuous electrical oscillations, a substantially vertical antenna, a substantially horizontal antenna and means for impressing said oscillations upon the respective antennæ in cyclically varying amounts.

10. A transmitter for radiant energy comprising means for generating continuous electrical oscillations, a substantially vertical antenna, a substantially horizontal antenna and means for impressing said oscillations substantially alternatively on said antennæ at a predetermined frequency.

11. A transmitter for radiant energy enabling energy to be received without fading, comprising means for generating continuous electrical oscillations, a substantially vertical antenna, a substantially horizontal antenna and means for causing said oscillations to be impressed at different times substantially exclusively on the respective antennæ and to cause energy to be impressed upon said antennæ at the intermediate periods in inversely varying amounts.

12. A transmitter for radiant energy comprising means for generating continuous electrical oscillations, a substantially vertical antenna, a substantially horizontal antenna, means for impressing the electrical oscillations upon the antenna and means for utilizing electrical oscillations of a frequency different from that of the first mentioned oscillations to cause the first mentioned oscillations to be impressed upon the two antennæ in cyclically varying proportions.

13. A transmitter for radiant energy enabling energy to be received without fading, comprising means for generating continuous electrical oscillations, a substantially vertical antenna, a substantially horizontal antenna means for impressing said electrical oscillations on the antennæ and means for cyclically varying the proportion of said oscillations impressed upon the respective antennæ said last mentioned means including a vacuum tube oscillator for producing oscillations of different frequency from that of the first mentioned oscillations and three electrode control tubes inserted in the supply circuits of the antennæ respectively and having their grids connected to the output circuit of the vacuum tube oscillator so as to cause them to be simultaneously charged in opposite senses.

14. A transmitter for radiant energy enabling energy to be received without fading,

comprising means for generating continuous electrical oscillations, a substantially vertical antenna and a substantially horizontal antenna arranged at right angles to each other, means for impressing said oscillations upon the respective antennæ and means for tilting the wave front of the transmitted energy.

15. A transmitter for radiant energy comprising means for generating continuous electrical oscillations, a substantially vertical antenna, a plurality of substantially horizontal antennæ, means for impressing said oscillations upon the antenna means for causing the horizontal antennæ to produce a rotating field and means for cyclically varying the vertical angle of radiations of the transmitted energy.

16. The method of radio transmission which comprises, continuously and cyclically varying the vertical angle of the wave front of a signal wave and varying the total energy transmitted to send a signal.

17. The method of radio transmission which comprises, transmitting energy from adjacent substantially vertical and substantially horizontal antennæ, cyclically varying the amounts of energy supplied to the respective antennæ and varying the nature of the total electrical energy to send a signal.

18. A transmitter for radiant energy comprising, a source of high frequency oscillations, a plurality of antennæ arranged at angles to each other, means for impressing said high frequency energy upon said antennæ, signal means for modulating the energy transmitted through said antennæ, a source of lower supersonic frequency oscillations and means for causing said last mentioned oscillation to inversely and continuously vary the proportion of said modulated high frequency energy transmitted by each of said antennæ and thereby continuously vary the angle of the resultant wave front transmitted by said antennæ.

19. A method of eliminating fading in the reception of radiant energy which consists in transmitting energy from adjacent substantially vertical and substantially horizontal antennæ, varying inversely the amounts of energy supplied to the respective antennæ and varying the nature of the total electrical energy for the purpose of signaling.

20. The method of eliminating fading in the reception of radiant energy which comprises, cyclically varying the angle of radiation of the transmitted energy at a superaudible frequency lower than the carrier frequency and varying the nature of the total transmitted energy for the purpose of signalling.

21. A transmitter for radiant energy enabling energy to be received without fading,

comprising means for generating continuous electrical oscillations, a substantially vertical antenna, a substantially horizontal antenna, means for impressing said oscillations upon the respective antennæ in cyclically varying amounts and means for varying the total energy transmitted for the purpose of signalling.

22. A transmitter for radiant energy comprising means for generating continuous electrical oscillations, a substantially vertical antenna, a substantially horizontal antenna, means for impressing said oscillations substantially alternatively on said antennæ at a predetermined frequency and means for varying the total energy transmitted for the purpose of signalling.

23. A transmitter for radiant energy enabling energy to be received without fading, comprising means for generating continuous electrical oscillations, a substantially vertical antenna and a substantially horizontal antenna arranged at right angles to each other, means for impressing said oscillations upon the respective antennæ, means for tilting the wave front of the transmitted energy, and means for varying the total transmitted energy to send a signal.

24. A transmitter for radiant energy comprising means for generating continuous electrical oscillations, a substantially vertical antenna, a plurality substantially horizontal antennæ, means for impressing said oscillations upon the antennæ means for causing the horizontal antennæ to produce a rotating field, means for cyclically varying the vertical angle of radiations of the transmitted energy, and means for varying the total electrical energy transmitted to send a signal.

25. In combination a radiating system, means for changing the vertical directional radiating properties of said system cyclically and in a continuous manner at a speed which is comparable with the signalling speed, and means for varying the nature of the total electrical energy transmitted by the said radiating system for the purposes of signalling.

26. Radio transmission apparatus comprising a plurality of antennæ having differently directional characteristics, means to radiate signalling energy from each of said antennæ successively, means to continually change the distribution of signalling energy to said antennæ, an electron tube amplifier network for each antenna and an electron tube oscillator common to the several networks.

27. The method of radio transmission from a plurality of antennæ, at least one of which is non-directional, which comprises generating signalling energy of carrier-wave frequency, impressing said energy successively upon each of said antennæ, and cyclically changing the energy radiated from said antennæ so that each signalling impulse shall

comprise successive radiation from at least two of said antennæ.

28. The method of overcoming fading in radio transmission from a pair of antennæ, each of said antennæ being energized through its respective electron tube amplifier network, which comprises generating signalling energy of carrier-wave frequency, exciting the network of one antenna from half-cycles of one polarity of a single phase alternating current and exciting the network of the other antenna from oppositely polarized half-cycles of said single phase alternating current thereby radiating the signalling energy from the two said antennæ successively.

29. A radio transmission system comprising a single high frequency electron tube oscillator, a power amplifier system connected with said oscillator said power amplifier system having a plurality of independent output circuits and separate antennæ connected with said output circuits for the radiation of signalling energy, and means for effecting radiation first on one antenna and then on the other antenna in successive order in predetermined timed relation.

30. A radio transmission system comprising an electron tube oscillator circuit, an amplification system comprising a plurality of power amplifier tubes each having input and output circuits with the input circuits thereof connected with the output circuit of said oscillator circuit, a separate antenna having different radiation characteristics independently coupled with each of said output circuits of said power amplifier, and means connected with said output circuits for alternately effecting radiation on each of said antennæ in successive periods, the radiation of energy from one antennæ being displaced with respect to the radiation of energy from another of the separate antennæ.

31. A high frequency transmission system comprising a plurality of antennæ of different characteristics at least one of which is non-directional, an oscillator for supplying current of the same frequency to said antennæ, and an amplifier for cyclically varying the impression of amplified energy from said oscillator to said antennæ.

32. A high frequency transmission system in accordance with claim 31 in which said amplifier comprises a plurality of vacuum tubes, and a source of alternating current for rendering said tubes alternatively effective.

33. The method of overcoming fading in the radio transmission of signalling energy from two antenna networks which comprises generating a high frequency carrier current, generating a second alternating current of different frequency, impressing said high frequency carrier current successively upon each of said networks, and transferring the radiation effect from one antenna to another.

at the frequency of said second alternating current.

34. A radio transmission system comprising an electron tube network for generating high frequency oscillations, a power amplifier system having a common input circuit and a plurality of tuned output circuits, separate antennæ coupled to each of said output cir-

cuits and electrical means for automatically successively rendering said output circuits effective for the radiation of signalling energy in predetermined timed relation, the radiated energy from one antenna being displaced with respect to the radiation of energy from another antenna. 70
